US0D1043380S

(12) **United States Design Patent** (10) **Patent No.:** **US D1,043,380 S**
(45) **Date of Patent:** **** Sep. 24, 2024**

(54) **LASER DISTANCE METER**

(71) Applicant: **MILESEEY TECHNOLOGY (US) INC.**, City of Industry, CA (US)

(72) Inventors: **Long Luo**, Shenzhen (CN); **Zhi Chou**, Shenzhen (CN)

(73) Assignee: **MILESEEY TECHNOLOGY (US) INC.**, City of Industry, CA (US)

(**) Term: **15 Years**

(21) Appl. No.: **29/939,991**

(22) Filed: **Apr. 30, 2024**

(51) LOC (14) Cl. **10-04**

(52) U.S. Cl.

USPC **D10/70**

(58) **Field of Classification Search**

USPC D10/62, 65, 69, 70, 71, 74, 75, 78, 80

CPC G01C 1/00

See application file for complete search history.

(57) **CLAIM**

The ornamental design for a laser distance meter, as shown and described.

DESCRIPTION

FIG. 1 is a perspective view of a laser distance meter showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the laser distance meter that form no part of the claimed design.

1 Claim, 8 Drawing Sheets
